RECLOSING CIRCUIT BREAKER SYSTEM

Howard G. MacDonald, Murrysville, and Allan W. Hill, Wilkinsburg, Pa., assignors to Westinghouse Electric & Manufacturing Company, East Pittsburgh, Pa., a corporation of Pennsylvania

Application December 7, 1935, Serial No. 53,384

22 Claims. (Cl. 175—294)

Our invention relates generally to electrical control systems and it has particular relation to circuit breaker reclosing systems.

The object of our invention, generally stated, is to provide a circuit breaker reclosing system which shall be simple and efficient in operation and which may be readily and economically manufactured and installed.

The principal object of our invention is to provide for simultaneously initiating sequences of functions for tripping a circuit breaker and reclosing it.

An important object of our invention is to provide for simultaneously energizing the tripping and closing windings of a circuit breaker.

Another object of our invention is to provide for simultaneously initiating sequences of functions for tripping a circuit breaker and reclosing it in response to a fault occurring on one of the circuits connected by the circuit breaker.

Still another object of our invention is to provide for simultaneously energizing the tripping and closing windings of a circuit breaker in response to a fault occurring on one of the circuits connected by the circuit breaker.

A further object of our invention is to provide for preventing the further reclosure of a circuit breaker during a predetermined interval after it has been reclosed and tripped.

Still another object of our invention is to provide for preventing further reclosure of a circuit breaker during a predetermined interval after it has been reclosed and tripped in response to a fault occurring and persisting on one of the circuits connected by the circuit breaker.

A concrete object of our invention is to provide a fault responsive relay connected to simultaneously effect the energization of the tripping and closing windings of a circuit breaker to immediately effect a reclosure thereof after it has been tripped in response to the occurrence of a fault.

Other objects of our invention will, in part, be obvious and, in part, appear hereinafter.

Accordingly, our invention will be disclosed in the embodiment hereof shown in the accompanying drawing and comprising the features of construction, combination of elements and arrangement of parts which will be exemplified in the constructions hereinafter set forth and the scope of the application of which will be indicated in the appended claims.

For a more complete understanding of the nature and scope of our invention reference may be had to the following detailed description, taken

in connection with the accompanying drawing, in which

Figure 1 illustrates diagrammatically a reclosing circuit breaker system organized in accordance with our invention;

Fig. 2 illustrates diagrammatically a reclosing circuit breaker system, similar to that shown in Fig. 1, having a fault responsive relay for controlling its function; and

Fig. 3 illustrates diagrammatically a circuit breaker reclosing system, similar to that shown in Fig. 2, having a time delay relay for preventing a second reclosure of the circuit breaker during a predetermined interval.

It is frequently desirable to effect a reclosure of a circuit breaker as soon as it is tripped in order that there may be a minimum of outage of the feeder circuit supplied from a power system through the circuit breaker. In many instances, a fault occurring on a line is of a temporary nature and is cleared during the time that a circuit breaker is momentarily opened. In such case, therefore, it is desirable to provide for tripping out the circuit breaker on the occurrence of a fault and to simultaneously initiate a sequence of functions which will effect the immediate reclosure of the circuit breaker.

In order to reclose a circuit breaker after it has been tripped, we have provided for simultaneously energizing the tripping and closing windings of a circuit breaker. By means of a single control device we have provided for effecting the energization of the tripping winding and at the same time the energization of the operating winding of an auxiliary relay which, in turn, is effective to connect the closing winding of the circuit breaker for energization to a current source. The auxiliary control relay operates within a very short interval and, therefore, the closing winding is energized at the same time that the tripping winding is energized although its energization is initiated from 5 to 6 cycles, of a 60-cycle source, for example, after the tripping winding is energized.

In a modification of the invention, we have provided for effecting substantially simultaneous energization of the tripping and closing windings in response to the operation of a fault responsive relay. On the occurrence of a fault on one of the circuits interconnected by the circuit breaker, the fault responsive relay is operated to energize a tripping winding and to also energize the operating winding of the auxiliary relay. This relay, in turn, is effective, as set forth above, to energize the closing winding. Therefore, as soon

as the circuit breaker is tripped out, it is immediately reclosed with a minimum of delay.

In the event that the fault still persists on the system, it is desirable that the circuit breaker 5 be instantly reclosed only a single time and that the system be prevented from reclosing more than a single time in response to the occurrence of a fault. This operation is called pumping. With a view to preventing the pumping of the circuit breaker, a time delay relay is provided which is effective to prevent a second energization of the closing winding during a predetermined interval after the fault responsive relay has been operated. By this means, if the fault persists 10 after the first tripping operation, the circuit breaker will not be reclosed a second time.

Referring now particularly to Fig. 1 of the drawing it will be observed that the reference character 10 designates, generally, a circuit breaker which is arranged to connect circuits 11 and 12 which have been represented by conductors. The circuit breaker 10 is provided with a closing winding 13W and a tripping winding 14W. It will be understood that the representation of the circuit breaker 10 is diagrammatic only and that it is employed merely to illustrate the novel features of my invention.

In order to simultaneously initiate one sequence of functions for tripping the circuit breaker and another sequence of functions for immediately reclosing it, a control switch, shown generally at 15, is provided having contact members 15a and 15b which are arranged to be bridged by means of a bridging member 15c. Since it is desirable 30 to provide a special control feature in conjunction with the closing winding 13W, an auxiliary control relay 16 is provided having contact members 16a which are arranged to complete an energized circuit for the closing winding 13W. 40 When the circuit breaker 10 is closed to a predetermined position, it is desirable to open the energizing circuit for the closing winding 13W. This is effected by means of a releasing winding 16RW associated with the auxiliary control relay 16 as 45 illustrated, and, when energized, it is effective to break the mechanical connection between the bridging member 16B for the contact members 16a and the armature 16AR operated by the winding 16W. A control switch, shown generally at 50 17, is also provided for initially effecting the closure of the circuit breaker 10.

In operation, it will be assumed that the control switch 17 is closed for the purpose of initially closing the circuit breaker 10. When the circuit breaker 10 is in the closed position, the control switch 15 may be operated to trip it and to immediately reclose it.

The circuit for energizing the operating winding 16W of the auxiliary control relay 16 in response to the operation of the control switch 17 60 may be traced from an energized conductor L1 through the conductor 40, contact members 17a, conductor 41, winding 16W and conductor 42 to an energized conductor L2. The circuit for energizing the closing winding 13W may be traced from the conductor L1 through conductor 43, contact members 16a, conductor 44, closing winding 13W and conductor 42 to conductor L2.

As soon as the circuit breaker 10 reaches a 70 predetermined position in its travel to the closed position, a circuit is completed at contact members 10b for energizing the releasing winding 16RW of the auxiliary control relay 16. As a result of its energization, the mechanical connection between the armature 16AR and the

bridging member 16B is broken and they are opened. As a result, the energizing circuit for the closing winding 13W is opened. In this manner, regardless of how long the control switch 17 is held in the operated position, current will be supplied to the closing winding 13W only for a time sufficiently long to close the circuit breaker 10.

The circuit for effecting energization of the releasing winding 16RW may be traced from the conductor L1 through conductor 40, contact members 17a, conductor 41, releasing winding 16RW, conductor 45, contact members 10b and conductor 46 to the conductor L2.

As soon as the control switch 17 is released, the 15 energizing circuit for the operating winding 16W of the auxiliary control relay 16 is opened and it is deenergized.

The control switch 15 may now be operated to simultaneously effect the energization of the tripping winding 14W and the closing winding 13W. There is a slight delay in initiating the energization of the closing winding 13W due to the provision of the auxiliary control relay 16. However, in practice, this time delay is slight. The 20 combination of the delay introduced by the greater time constant of the closing winding 13W as compared with the time constant of the tripping winding 14W and the operation of the auxiliary control relay 16 is sufficient to permit the circuit breaker 10 to be opened sufficiently far 25 enough to break the arc drawn between the contact members of the circuit breaker 10 before the closing winding 13W is energized to effect the 30 reclosure.

The circuit for energizing the tripping winding 14W may be traced from the conductor L1 through conductor 47, contact members 15a bridged by the member 15c, conductor 48, tripping winding 14W, conductor 49, contact members 10a and conductor 46 to conductor L2.

It is obvious that the contact members 15b complete a circuit which is identical with that completed by the control switch 17 and, therefore, the circuit for energizing the operating winding 16W of the auxiliary control relay 16 will not be retraced. It will, however, be understood that on operation of the control switch 15, the tripping winding 14W is energized and at the same time the operating winding 16W of the auxiliary control relay 16 is also energized. As soon as contact members 16a are bridged, the closing winding 13W is energized. Since the time required for the operation of the auxiliary control relay 16 is a matter of a few cycles as measured by a 60-cycle current, the tripping and closing windings are energized substantially simultaneously. It is, therefore, possible to immediately effect a reclosure of the circuit breaker 10 as soon as it is tripped.

Referring now particularly to Fig. 2 of the drawing, it will be observed that a circuit is there shown which is adapted for control in response to the occurrence of a fault on one of the circuits, for example the circuit 12, to effect the tripping out and the reclosure of the circuit breaker 10. For this purpose a current transformer 20 is provided which is connected to effect the energization of the operating winding 21W of a fault responsive relay 21. The contact members 21a of this relay may be considered to perform the same function as the contact members 15a and 15b of the control switch 15, shown in Fig. 1. In order to provide for manual control of the circuit 75

breaker 10, a closing switch 22 and a tripping switch 23 are provided.

The circuit breaker 10 may be initially closed by operating the closing switch 22. In response to the operation of the closing switch 22, the operating winding 16W of the auxiliary control relay 16 is energized and at contact members 16a a circuit is completed for energizing the closing winding 13W as set forth hereinbefore. When the circuit breaker reaches a predetermined position, a circuit is completed at contact members 10b for completing the energization of the releasing winding 16RW of the auxiliary control relay 16. The closing winding 13W is then deenergized.

Since the circuits for effecting the energization of the operating winding 16W, completed at contact members 22b, and for energizing the releasing winding 16RW are the same as traced in connection with Fig. 1, they will not be retraced.

Assuming now that a fault occurs on the circuit 12, such as a short circuit, and that sufficient current flows through the operating winding 21W to cause the contact members 21a of the fault responsive relay 21 to be bridged, then a circuit is completed for simultaneously effecting the energization of the tripping winding 14W and the operating winding 16W of the fault responsive relay 16. The circuit breaker 10 is then permitted to move toward the open position. Before it reaches the full open position, however, the closing winding 13W is energized to reclose the circuit breaker. As a result, the connection between the circuits 11 and 12 is only momentarily broken and is restored immediately.

The circuit for effecting the energization of the tripping winding 14W may be traced from the conductor L1 through conductor 50, contact members 21a, conductor 51, winding 14W, conductor 49, contact members 10a and conductor 46 to the conductor L2. The circuit for energizing the operating winding 16W of the auxiliary control relay may be traced from the conductor L1 through conductor 50, contact members 21a, conductors 51 and 52, contact members 23a, conductor 53, contact members 22a, conductor 41, winding 16W, and conductor 42 to conductor L2.

As soon as contact members 10b are bridged by the circuit breaker 10 being reclosed to a predetermined position, a circuit is completed for effecting the energization of the releasing winding 16RW over the circuit previously traced for energizing the winding 16W. At contact members 16a the energizing winding for the closing winding 13W is opened and it is deenergized. In the event that it is desired to manually close the circuit breaker 10, the closing switch 22 may be operated to bridge contact members 22b. Likewise, if it is desired to trip the circuit breaker manually, the tripping switch 23 may be operated.

At contact members 23b, a circuit is completed for effecting the energization of the tripping winding 14W. At contact members 23a, the circuit is opened for energizing the operating winding 16W of the auxiliary control relay 16 and, therefore, when the tripping switch 23 is operated, the circuit breaker 10 will not be immediately reclosed.

Referring now particularly to Fig. 3 of the drawing, it will be noted that a circuit similar to that shown in Fig. 2 is illustrated. However, in order to prevent the circuit breaker 10 from pumping in the event that the fault still persists after a single reclosure, a time delay relay, shown generally at 30, is provided. The time delay relay 30 is arranged to maintain the operating

winding 16W of the auxiliary control relay 16 energized during a predetermined interval after the last operation of the fault responsive relay 21 so that the circuit breaker 10 will be reclosed only one time in the event of a fault.

The time delay relay 30 is provided with an E-shaped armature core on the center leg of which a neutralizing winding 30N is positioned. This winding is connected directly across the conductors L1 and L2 for energization. An operating winding 30W is also provided on the middle leg which, when energized, is arranged to cause the contact members 30a to be closed. By means of the adjusting spring 31, the time required for the contact members 30a to open after the operating winding 30W is deenergized may be varied. The time delay relay 30 is of the type disclosed in Patent 1,753,983 issued April 8, 1930, to W. G. Cook, and assigned to the assignee of this application.

For the purpose of manually closing the circuit breaker 10, the control switch 17, shown in Fig. 1, may be provided. For manually tripping the circuit breaker 10, the control switch 23, shown in Fig. 2 may be used.

In operation, the circuit breaker 10 may be closed by manually operating the closed switch 17. In response to the operation of this switch, the auxiliary control relay 16 is operated to effect the energization of the closing winding 13W. The releasing winding 16RW is energized when the contact members 10b are bridged and the closing winding 13W is then deenergized. In like manner, the circuit breaker may be manually tripped by operating the control switch 23. When this switch is operated, only the tripping winding 14W will be energized.

Assuming now that the circuit breaker 10 has been closed and that a fault occurs on the circuit 12 of such magnitude that the operating winding 21W of the fault responsive relay 21 is sufficiently energized to bridge the contact members 21a, a circuit, which has previously been traced, will then be completed to effect the energization of the tripping winding 14W and the circuit breaker 10 will be permitted to move to the open position. At the same time, a circuit is also completed for effecting the energization of the operating winding 30W of the time delay relay 30. Contact members 30a are then closed to complete a circuit for effecting the energization of the operating winding 16W of the auxiliary control relay 16. In turn, the closing winding 13W of the circuit breaker 10 is energized. This circuit is opened as soon as contact members 16a are opened since contact members 10b are closed to effect the energization of the releasing winding 16RW.

The circuit for effecting energization of the operating winding 30W may be traced from the conductor L1 through conductor 50, contact members 21a, conductor 60, contact members 23a, conductor 61, winding 30W and conductors 62 and 42 to the conductor L2. The circuit for energizing the operating winding 16W may be traced from conductor L1 through conductors 50 and 63, contact members 30a, conductors 64 and 41, winding 16W, and conductor 42 to conductor L2.

Due to the fact that contact members 30a remain closed for a predetermined time after the operating winding 30W is deenergized by opening of contact members 21a of the fault responsive relay 21, the circuit for energizing the winding 16W of the auxiliary control relay 16 will be maintained. If, on reclosure of the circuit

breaker 10, the fault still persists, the fault responsive relay 20 will again be operated to again effect the energization of the operating winding 30W of the time delay relay 30. Since contact members 30a have meanwhile remained in the closed position, the time interval will be reinitiated and will now begin at the time that the contact members 21a of the fault responsive relay 21 are opened the second time. The reclosure of these contact members, however, effects a second energization of the tripping winding 14W and the circuit breaker 10 is again tripped. Since the operating winding 16W of the auxiliary control relay 16 has not been deenergized, the mechanical connection between its armature 16AR and the bridging contact member 16B is not restored. As a result, the closing winding 13W is not reenergized and, therefore, the circuit breaker 10 is only reclosed a single time.

After the expiration of the time interval for which the time delay relay 30 is adjusted, the contact members 30a are opened and the circuit for effecting the energization of the operating winding 16W of the auxiliary control relay 16 is opened. No further functioning of the system takes place until the circuit breaker 10 is manually reclosed by operation of the closing switch 17.

30 Since certain further modifications may be made in the foregoing constructions and different embodiments of the invention may be made without departing from the scope thereof, it is intended that all matters shown in the accompanying drawing, or set forth in the foregoing specification, shall be interpreted as illustrative and not in a limiting sense.

We claim as our invention:

1. A reclosing circuit breaker system comprising, in combination, closing means for the circuit breaker, tripping means for the circuit breaker, and control means for substantially simultaneously effecting the functioning of said closing and tripping means when the circuit breaker is in the closed position, said control means including means controlled by the circuit breaker for rendering the closing means ineffective to again immediately reclose the breaker.

45 2. A reclosing circuit breaker system comprising, in combination, tripping means for the circuit breaker, closing means for the circuit breaker, means for initiating the operation of said tripping means when the circuit breaker is in the closed position, and relay means disposed to be responsive to the operation of said means for initiating the operation of said closing means, said relay means being further responsive to the closure of the circuit breaker to render the control means ineffective to immediately 50 initiate a second operation of the closing means.

60 3. An operating system for a circuit breaker comprising, in combination, a closing winding disposed to operate the circuit breaker to the closed position, a tripping winding disposed to release the circuit breaker for movement to the open position, and switch means having open and closed operating positions for substantially simultaneously effecting when operated to the closed position the energization of said windings when the circuit breaker is closed to trip it and immediately initiate a reclosure thereof before the full open position is reached and means responsive to the closing operation of the breaker 65 operable to preclude a subsequent re-energiza-

tion of the closing winding until the switch means has been operated to the open position.

4. An operating system for a circuit breaker comprising, in combination, a tripping winding disposed to release the circuit breaker for movement to the open position, a closing winding disposed to operate the circuit breaker to the closed position, control means for effecting the energization of said tripping winding when the circuit breaker is in the closed position, and auxiliary control means disposed to be responsive to the operation of said control means for effecting the energization of said closing winding to immediately reclose the circuit breaker, said auxiliary control means being rendered ineffective 15 to maintain the closing winding energized in response to the closure of the circuit breaker.

5. A reclosing circuit breaker system comprising, in combination, a tripping winding disposed to release the circuit breaker for movement to the open position, a closing winding disposed to operate the circuit breaker to the closed position, switch means disposed to connect said tripping winding to a current source when the circuit breaker is in the closed position, an auxiliary 20 control relay disposed to be operated on operation of said switch means for connecting said closing winding to said current source to immediately 25 effect a reclosure of the circuit breaker, and means responsive to the closure of the circuit breaker for effecting the opening of the auxiliary 30 relay to deenergize the closing winding.

6. A system for reclosing a circuit breaker interconnecting two electrical circuits comprising, in combination, tripping means for the circuit breaker, closing means for the circuit breaker, means disposed to be operated in response to the occurrence of a fault on one of said 35 circuits for substantially simultaneously effecting the functioning of said tripping and closing 40 means, and means responsive to the closure of the circuit breaker for rendering the closing means ineffective.

7. A system for reclosing a circuit breaker interconnecting two electrical circuits comprising, in combination, tripping means for the circuit breaker, closing means for the circuit breaker, means disposed to be operated on the occurrence of a fault on one of said circuits for initiating the operation of said tripping means, 45 means operable in response to the operation of said fault responsive means for initiating the operation of said closing means, and means actuated on closure of the circuit breaker for rendering said last mentioned means ineffective to again 50 initiate the operation of the closing means so long as the fault responsive means is in its operated condition.

8. A system for reclosing a circuit breaker interconnecting two electrical circuits comprising, in combination, a tripping winding disposed to release the circuit breaker for movement to the open position, a closing winding disposed to operate the circuit breaker to the closed position, means disposed to be operated on the occurrence 60 of a fault on one of said circuits for substantially simultaneously effecting the energization of said windings to trip and immediately reclose the circuit breaker, and means responsive to the closure of the breaker for rendering the last named 65 means ineffective to again reclose the breaker so long as the fault exists.

9. A system for reclosing a circuit breaker interconnecting two electrical circuits comprising, in combination, a tripping winding disposed 70 75

to release the circuit breaker for movement to the open position, a closing winding disposed to operate the circuit breaker to the closed position, relay means disposed to be operated on the occurrence of a fault on one of said circuits for effecting the energization of said tripping winding, an auxiliary relay having a releasable contact element operable in response to the operation of said relay means for effecting the energization of said closing winding to immediately reclose the circuit breaker, and means operated in response to the closure of the circuit breaker effecting the release of said contact element to deenergize the closing winding while the auxiliary relay is still energized.

10. A system for reclosing a circuit breaker interconnecting two electrical circuits comprising, in combination, a tripping winding disposed to release the circuit breaker for movement to the open position, a closing winding disposed to operate the circuit breaker to the closed position, a relay disposed to be operated on the occurrence of a fault on one of said circuits for connecting said tripping winding to a current source, and an auxiliary relay disposed to be operated on the operation of said fault responsive relay for connecting said closing winding to said current source, before the breaker reaches its full open position to immediately effect a reclosure of the circuit breaker, said auxiliary relay being operated in response to the closure of the breaker to disconnect the closing winding from the current source.

11. A system for reclosing a circuit breaker interconnecting two electrical circuits comprising, in combination, tripping means for the circuit breaker, closing means for the circuit breaker, means disposed to be responsive to the occurrence of a fault on one of said circuits for substantially simultaneously initiating one sequence of operation to effect the functioning of said tripping means and another sequence of operation to effect the functioning of said closing means, means responsive to the closure of the breaker for terminating said other sequence, and time delay means for preventing the reinitiation of said other sequence during a predetermined interval.

12. A system for reclosing a circuit breaker interconnecting two electrical circuits comprising, in combination, tripping means for the circuit breaker, closing means for the circuit breaker, means disposed to be operated on the occurrence of a fault on one of said circuits for initiating the operation of said tripping means, and means including time delay means operable in response to the operation of said fault responsive means for initiating the operation of said closing means, means operated in response to the closure of the breaker for rendering said means ineffective, said time delay means being operable to prevent a subsequent operation of said closing means during a predetermined interval.

13. A system for reclosing a circuit breaker interconnecting two electrical circuits comprising, in combination, a tripping winding disposed to release the circuit breaker for movement to the open position, a closing winding disposed to operate the circuit breaker to the closed position, means disposed to be responsive to the occurrence of a fault on one of said circuits for substantially simultaneously initiating one sequence of operation to effect the energization of said tripping winding and another sequence of operation to effect the energization of said closing winding,

means responsive to the closing operation of the breaker for deenergizing the closing winding, and time delay means disposed to prevent the reenergization of said closing winding during a predetermined interval after said fault responsive means is operated.

14. A system for reclosing a circuit breaker interconnecting two electrical circuits comprising, in combination, a tripping winding disposed to release the circuit breaker for movement to the open position, a closing winding disposed to operate the circuit breaker to the closed position, means disposed to be operated on the occurrence of a fault on one of said circuits for effecting the energization of said tripping winding, time delay means disposed to be responsive to the operation of said fault responsive means, said time delay means being characterized by having contact members which are quickly closed and delayed in opening, auxiliary means disposed to be operated on closure of said contact members for effecting the energization of said closing winding, and means disposed to be operated when the circuit breaker reaches a predetermined position for rendering said auxiliary means ineffective to maintain said closing winding energized.

15. A system for reclosing a circuit breaker interconnecting two electrical circuits comprising, in combination, a tripping winding disposed to release the circuit breaker for movement to the open position, a closing winding disposed to operate the circuit breaker to the closed position, a relay disposed to be operated on the occurrence of a fault on one of said circuits for connecting said tripping winding to a current source, a time delay relay disposed to be responsive to the operation of said fault responsive relay, said time delay relay being characterized by having contact members which are quickly closed and delayed in opening, an auxiliary relay disposed to be operated on closure of said contact members, said auxiliary relay having contact members disposed to connect said closing winding to said current source, and releasing means disposed to be operated when the circuit breaker reaches a predetermined position for releasing the operating connection between said last named contact members and said auxiliary relay.

16. A control system for a circuit interrupter interconnecting a plurality of electric circuits comprising, first means operable to cause the interrupter to connect the circuits together, second means operable to cause the interrupter to disconnect the circuits, means operable to initiate the substantially simultaneous operation of the first and second means, and means for rendering said first means ineffective in response to the operation of the interrupter to connect the circuits together, thereby to effect a substantially instantaneous first reconnection of the circuits and preclude an immediate second reconnection thereof.

17. The combination with a circuit interrupter having opening and closing means, of control means operable to substantially simultaneously effect the operation of the opening and closing means, and means responsive to the closure of the interrupter for thereafter rendering the closing means ineffective.

18. The combination with a circuit interrupter having opening and closing means, of relay means including an auxiliary relay operable to substantially simultaneously effect the operation of the opening and closing means, and means responsive to the closing operation of the inter-

rupter for controlling the auxiliary relay to thereafter render the closing means ineffective.

19. The combination with a circuit interrupter for controlling an electric circuit, of means for effecting a substantially instantaneous reclosure of the circuit including fault responsive means for effecting the operation of the interrupter to open the circuit, and means including auxiliary relay means controlled by the fault responsive 5 means for effecting operation of the interrupter to reclose the circuit, said auxiliary relay means being rendered ineffective in response to the operation of the interrupter to reclose the circuit thereby to preclude an immediate second 10 closure of the circuit.

20. The combination with a circuit interrupter for electric circuits, of means for effecting a substantially instantaneous reclosure of the circuit including fault responsive means for operating 15 the interrupter to effect an opening of the circuit, an auxiliary relay responsive to the fault responsive means for operating the interrupter to effect a substantially instantaneous reclosure of the circuit, and means operated in response to the 20 operation of the interrupter to reclose the circuit for thereafter rendering said auxiliary relay ineffective to operate the interrupter to effect an immediate second reclosure of the circuit.

21. The combination with a circuit interrupter 25 operable to open and close electrical circuits and having opening and closing means, of an auxil-

iary relay operable to effect the operation of the closing means of the interrupter, said auxiliary relay being further operable when in its operated position to render the closing means ineffective, means operable to effect the operation of the opening means of the interrupter and the auxiliary relay at substantially the same time to provide for opening the interrupter and reclosing it immediately, and means responsive to the closing operation of the interrupter for effecting the said further operation of the auxiliary relay to preclude an immediate second reclosure. 5 10

22. The combination with a circuit interrupter for controlling the connection between electric circuits having opening and closing means, of a 15 circuit for energizing the closing means, a circuit for energizing the opening means, an auxiliary relay for controlling the energization of the circuit for the closing means, said relay having releasable contact members and electro-responsive 20 releasing means therefor, an operating circuit for the auxiliary relay, relay means operable to control the energization of the circuits for the opening means and the auxiliary relay, and an energizing circuit for the electro-responsive releasing 25 means of the auxiliary relay controlled in accordance with the closing operation of the interrupter to render the closing means ineffective.
